UNITED STATES PATENT OFFICE.

JAMES W. SHATTO, OF LORIMOR, IOWA.

ROAD SCRAPER.

Application filed May 21, 1925. Serial No. 31,865.

To all whom it may concern:

Be it known that I, JAMES W. SHATTO, a citizen of the United States, residing at Lorimor, in the county of Union and State 5 of Iowa, have invented certain new and useful Improvements in Road Scrapers, of which the following is a specification.

This invention relates to road machinery and has for its object the provision of a road scraper of inexpensive construction which will be strong and durable and will operate efficiently to reduce to a smooth level condition all rough broken up surfaces. The invention seeks to provide a 10 road scraper which, as it is drawn over the surface of a road, will act progressively thereon so as to treat the entire surface and reduce all ruts and projections to a smooth level condition, means being provided to 15 permit the machine at will to scrape the surface or to travel without a scraping action. The invention also has for its object the provision of easily operated simple means for adjusting the machine so that it will be 20 operative or inoperative as may be desired. The invention is illustrated in the accompanying drawings and will be hereinafter 25 fully set forth.

In the drawings:

30 Figure 1 is a plan view of my improved road scraper;

Fig. 2 is a central longitudinal section of the same;

Fig. 3 is an enlarged sectional elevation 35 of the mounting for the front roller;

Fig. 4 is an enlarged detail section on the line 4—4 of Fig. 2;

Fig. 5 is an enlarged view of a portion 40 of the adjusting mechanism;

Fig. 6 is an enlarged detail section on the line 6—6 of Fig. 2, and

Fig. 7 is a detail perspective of a scraper 45 blade.

In carrying out the invention, I employ 50 two side bars or beams 1 which are arranged in forwardly converging relation, as shown clearly in Fig. 1, and on the under side of which are scraper blades 2 which are disposed equi-distantly along the side bars and at an angle to the longitudinal axis of the same. These scrapers are of such width that they are in overlapping relation longitudinally of the machine and, consequently, as the machine is drawn over

the surface of a road, the blades will act 55 progressively thereon and treat the entire area thereof so that it will be reduced to a smooth level condition free of all ridges or ruts. To the front ends of the side bars 1, I secure, preferably by welding, the plow 60 blades 3 which converge to the medial central line of the machine, as shown in Fig. 1, and then extend forward along said line to be secured to the lower end of a clevis post 4 at opposite sides of the same, as will 65 be understood upon reference to Figs. 1 and 2 of the drawings. The clevis post is provided adjacent its front edge with a plurality of openings 5, in any one of which a draft device may be engaged. It will be 70 noted that the plows 3 are of such extent that their rear ends overlap the foremost scrapers 2 and, consequently, avoid the formation of a central ridge in the path traveled by the machine. The forwardly 75 projecting portion of the plow constitutes a point which will make an entering cut in transverse ridges presented to the travel of the plow so that such ridges will not form an obstruction turning aside the machine 80 but will be engaged and quickly reduced to a level condition. The scraper blades 2 may be secured directly to the side bars 1 but I have found it desirable to weld the blades 85 to sleeves 6 which may be held in fixed positions on the side bars by set screws 60 in an obvious manner. The side bars are flat-sided in cross section and the bores of the sleeves are of corresponding contour so that rotation of the sleeves about the side bars 90 will be prevented. Some of the sleeves are provided with vertically disposed lugs or ears 61, and cross bars 7, 8 and 9 of circular cross section are secured to and extend between the corresponding lugs or ears, securing 95 bolts 11 being inserted through the ends of the cross bars and the lugs so that the cross bars will be rigidly secured in place. Rearwardly diverging downwardly inclined braces 12 extend between and are secured to 100 the clevis post 4 and the front cross bar 7 so that a rigid structure at the front end of the machine is attained. A platform 13 is hung in any convenient or preferred manner upon the intermediate cross bar 8 and 105 the rear cross bar 9.

Mounted for rocking movement upon the front cross bar 7 is a crank arm 14 which

rises therefrom and has a vertically disposed hub or sleeve 15 on its rear side. Fitted within the said hub or sleeve is the vertical spindle 16 having a fork 17 extending rearwardly from its lower end, a roller 18 being carried within the rear end of the fork. The spindle 16 may be retained within the hub sleeve by any convenient means, such as a pin 19, inserted through its upper end above the upper end of the sleeve. The roller 18 is a caster roller, being free to swing to either side so that it will automatically accommodate itself to the line of travel. Mounted for rocking movement upon the rear cross bar 9 are a plurality of rearwardly extending crank arms 20 carrying a connecting bar or axle member 21 in their rear ends, and upon the ends of this axle member 21 are mounted rollers 22 which 20 constitute rolling supports for the rear end of the machine when the scrapers are not to operate. Rising from the cross bar 9 is a crank arm 23 which is parallel to the crank arm 14, the upper ends of the said cranks 25 14 and 23 being connected by a connecting rod 24 having its ends pivoted to the upper extremities of the respective cranks whereby a like movement is imparted to both the front and the rear roller-carrying 30 elements and, consequently, equal and simultaneous adjustment of the same is effected. Upon the rear portion of the connecting rod 24 is mounted a seat 25 so that the operator may ride upon the machine. A 35 connecting link 26 is extended between the upper end of the crank 23 and the axle member 21 to brace and strengthen the structure and insure instant response of the axle to the operation of the adjusting mechanism. 40 The lower end of the crank 23 is preferably integral with the intermediate crank 20 thus forming an angle lever and attaining strength.

Upon the intermediate cross bar 8 at the center of the same, I erect a pair of standards or posts 27 and between the upper ends of said posts and the outer ends of the front cross bar 7 forwardly and downwardly diverging braces 28 extend to impart the desired rigidity to the structure. In the upper ends of the said posts and braces, I pivotally engage the trunnions 29 extending diametrically from a collar 30 which is disposed between the posts, the extremities of the trunnions being threaded, as shown at 31, to receive nuts 32 which, when they are turned home against the braces will firmly secure the collar in place. Extending through the collar 30 is an adjusting rod 33 which may 50 rotate freely in the collar but is held against endwise movement by stop collars 34 secured upon the rod at opposite sides of the supporting collar, as will be readily understood. The forward portion of the rod 33 is 55 threaded, as shown at 35, and a hand wheel 60

36 is secured upon its rear extremity whereby an operator upon the seat 25 may readily turn the rod to effect the desired adjustment. The threaded portion of the rod engages with the threaded bore of a nut 37 which is 70 secured between the upper ends of links 38 extending forwardly and having their front ends pivoted to the upper extremity of the crank 14. It will now be readily seen that, when the hand wheel 36 is turned, the rod 75 33 will rotate and the nut 37 will be caused to move longitudinally of the rod and, consequently, effect swinging movement of the crank 14, this movement being imparted through the connecting rod 24 to the rear 80 cranks and, consequently, the rollers 18 and 22 will be raised or lowered as may be desired.

From the foregoing description, taken in connection with the accompanying drawings, it will be seen that I have provided an exceedingly strong, compact and inexpensive machine which will effectually scrape the surface of a road so as to reduce it to a smooth level condition. The scrapers will 90 act progressively upon the ridges of the road and will deflect the loose dirt cut from the ridges inwardly, and this loose dirt will be pushed into the hollows or ruts so that the ruts and hollows will be filled and the 95 hummocks and ridges cut away. Ordinarily, the use of the scrapers alone will effect the desired results but if it be desired to more completely fill all the ruts and hollows a drag chain 40 may be attached to the rear 100 ends of the side bars 1 and to the axle member 21 so as to extend transversely of the machine and drag upon the ground to pull forward the loose surface dirt left by the scrapers, the drag chain effectually pulverizing the clods and dragging them forward so that they will drop into and fill the 105 hollows and ruts which may have escaped filling as the scrapers passed over the road. When the scrapers are to act, the hand wheel 110 36 is turned in the proper direction to feed the nut 37 forwardly, thereby rocking the cranks forwardly and lifting the rollers 18 and 21 from the ground, whereupon the weight of the machine will rest upon the 115 scrapers. If the machine is to be moved from one road to another or is to make a return trip over a leveled surface, the hand wheel 36 is manipulated to effect downward movement of the rollers 18 and 22 so that the weight of the machine will rest upon the rollers and the scrapers will be held 120 clear of the surface.

Having thus described the invention, I 125 claim:

1. A road scraper comprising rearwardly diverging side bars, depending scraper blades rigidly secured to the side bars at intervals along the same, plow blades secured to the front ends of the side bars 130

and having their front ends connected, and means for applying draft through the plow blades to the side bars.

2. A road scraper comprising rearwardly diverging side bars, depending scraper blades rigidly secured to said bars, cross bars mounted upon and extending between the side bars to maintain them in fixed relation, crank arms mounted for rocking movement upon the front and rear cross bars and rising from the respective bars in parallel relation, rollers supported from the said cross bars and connected with the respective cranks, a connecting bar connecting the upper ends of the cranks, and means supported upon an intermediate cross bar and connected with the forward crank to rock the cranks and effect vertical adjustment of the rollers.

3. A road scraper comprising rearwardly diverging side bars, depending scraper blades rigidly secured to said bars, a plurality of cross bars carried by and extending between the side bars, rollers supported on the front and rear cross bars for vertical rocking movement, cranks rising from the front and rear cross bars and connected with the respective rollers, a connecting bar extending between and pivoted to the upper ends of the respective cranks, a post rising from an intermediate cross bar, a rotatable rod swiveled upon the said post and having its forward portion threaded, a nut engaged upon the threaded portion of the said

rod, and links attached to the said nut and 35 having their forward ends pivoted to the crank upon the front cross bar.

4. A road scraper comprising rearwardly diverging side bars, sleeves fitted on the side bars and held against rotation about the 40 same, scraper blades fixed to the under sides of the sleeves, cross bars secured to and extending between some of the sleeves, supporting rollers carried by the cross bars, means for vertically adjusting the rollers 45 whereby to set either the rollers or the scraper blades in contact with a road, plow blades rigidly secured to and connecting the front ends of the side bars, and a draft device carried by the plow blades. 50

5. A road scraper comprising rearwardly diverging side bars, depending scraper blades rigidly secured to the side bars, a plurality of cross bars carried by and extending between the side bars, cranks rising from the front and rear cross bars, a connecting rod attached to and extending between the upper ends of said cranks, a supporting roller swiveled upon the forward crank, cranks secured to and extending rearwardly from the rear cross bar, an axle fitted through the rear ends of the rearwardly extending cranks, rollers mounted on the axle, and means connected with the connecting rod for rocking the cranks. 55 60 65

In testimony whereof I affix my signature.

JAMES W. SHATTO. [L. S.]
